UNITED STATES PATENT OFFICE.

WILLIAM C. SLEEMAN, OF BIRMINGHAM, ALABAMA.

SEVENTY-TON-CAR TRUCK.

Application filed October 12, 1928. Serial No. 312,056.

This invention aims to provide a simple design of car truck spring arrangement whereby the spring capacity can be readily increased from the present existing A. R. A. 5 standard capacity for the so-called seventy ton capacity railway cars. The invention aims to provide a design of spring grouping that will give increased spring capacity and which can be applied to different standard 10 capacity car trucks without change in dimensions of A. R. A. standard side frames and bolsters.

Heretofore in many cases where increased capacity springs have been applied to trucks, 15 the spring arrangements have been such that it was necessary to change the dimensions of side frames and bolsters, thus destroying the interchangeability of parts. This made it imperative for railroad companies to carry a 20 costly stock of spare parts.

With my improved design, I am able to provide increased spring capacity on existing equipment for various standard capacity cars merely by removing the A. R. A. standard 25 springs and applying my improved spring groups having the desired increased capacity.

The invention will be fully apparent from the following specification when read in connection 30 with the accompanying drawings and the features of novelty will be defined with particularity in the appended claims. In the drawings—

Fig. 1 is a horizontal section of one side 35 of a car truck embodying my invention;

Fig. 2 is a side elevation thereof;

Fig. 3 is a transverse section on line 3—3 of Fig. 1.

Referring in detail to the drawings, 1 40 represents a typical form of truck side frame having the usual tension member 2, compression member 3 and bolster columns 4. A spring plank 7 extends transversely between the side frames and rests on the tension member 2 between the column guides 4 as shown.

To secure the increased spring capacity for the truck, I provide a novel spring grouping shown in Fig. 1. The spring group is indicated 50 as a whole by numeral 10 and is made up of eight large spring units, the four spring units 10^a being large diameter, single coil springs and the spring units 10^b being double coil springs including small diameter inner springs 10^c.

The group of springs is so disposed with

respect to the frame that three spring units are arranged in a row along the longitudinal axis $x-y$ of the side frame. Of these three the two outer springs are double coil 60 springs as shown and the central single coil spring is positioned so that its axis lies at the intersection of a line $m-n$ extending through the center of the spring plank side frame and the center line $x-y$ of the side 65 frame. On the outer side of the center line $x-y$, I provide three single coil springs as clearly shown in Fig. 1 and on the inner side of the center line $x-y$ I provide two double coil springs which are staggered with respect to the three springs lying on the center line $x-y$. 70

The spring grouping shown in Fig. 1 and above described will not and is not intended to fit the standard spring plank. I, therefore, provide a specially shaped plank 7 which is increased slightly in width at its ends to accommodate the two rows of three springs which extend in the direction of the longitudinal axis $x-y$ of the side frame. 80 This additional width, however, does not prevent the application of the spring group to standard seventy ton A. R. A. side frames and bolsters. The springs are held by top and bottom retaining plates 12—12 having 85 projections 14 which are adapted to fit into holes 15 and 16, respectively, in the bolster 11 and the spring plank. The retainer plates are provided with centering projections 18 adapted to position the smaller inner springs 10^c. The plates are also formed with cup-like projections 17 which are perforated for the reception of retainer bolts 13 which connect the top and bottom plates. The depth of the projections 17 is sufficient 90 to permit working clearance for the ends of the bolts 13 when the springs are compressed under load.

In the improved design of spring arrangement, it will be seen that the group is unsymmetrical about the longitudinal center line $x-y$ of the frame. At least three springs (or more including the inner coils) being on the center line of the frame and three (or more if inner coils are used) being 100 located toward the outside of the frame and two single or double springs being located toward the inner part of the truck. This arrangement is provided so as to permit the spring plank 7 to be so formed that its side portions 25—25 can converge inwardly as 105 shown in plan in Fig. 1 to meet the portion 110

26 of the plank which is of a width corresponding to that of the standard A. R. A. spring plank. Thus, it is clear that I provide a spring plank which accommodates a 5 group of springs which will give an increased capacity and yet this spring plank has its inner portion 26 of standard width so as to provide the required clearance for adjacent parts of the standard car truck.

10 The group of springs described includes what I have called single coil and double coil springs. For convenience of description and for clarifying the intended meaning of the claims, I may say that the group 15 of springs as a whole is made up of spring units, the term spring unit being intended to cover either a single coil spring such as shown at 10^a or a double coil spring including a large outer spring as shown at 10^b and 20 a small inner spring as shown at 10^c.

Various modifications may be made without departing from the invention as defined in the appended claims.

What I claim is:—

25 1. A car truck of the character described including a side frame, a spring plank, a bolster and a group of at least eight spring units some of which lie on the longitudinal center line of the side frame, there being 30 more spring units on the outer side of said center line than on the inner side thereof.

2. A car truck of the character described comprising a side frame, bolster and a

spring plank, a group of at least eight spring units disposed between the spring 35 plank and bolster, said spring units being unsymmetrically arranged with respect to the center line of the side frame, there being a greater number of spring units on the outer side of said center line than on the inner 40 side thereof, three spring units being arranged in a row along said center line.

3. The car truck of claim 2 in which the inner portion of the spring plank is of standard A. R. A. width and the outer portion 45 thereof is of increased width to accommodate the said three springs arranged in a row on the center line of the said frame.

4. A seventy ton car truck having A. R. A. standard side frames and bolster and a special spring plank, the inner portion of which is of standard A. R. A. width and the end portion of which is of increased width yet of a size to fit the opening in said standard side frame and a group of eight spring units, 55 three of which lie on the longitudinal axis of said side frame, three more of which lie on the outer side of said longitudinal axis and two spring units lying on the inner side of the axis of the side frame and symmetrically arranged on opposite sides of the center line of the spring plank.

In witness whereof, I have hereunto signed my name.

WILLIAM C. SLEEMAN.
